UNITED STATES PATENT OFFICE.

ADOLPH H. DAUS, OF CHICAGO, ILLINOIS.

SAFETY DEVICE FOR ELECTRIC TRAINS.

No. 892,713.

Specification of Letters Patent.

Patented July 7, 1908.

Application filed December 30, 1907. Serial No. 408,570.

To all whom it may concern:

Be it known that I, ADOLPH H. DAUS, citizen of the United States, residing at Chicago, in the county of Cook and State of Illinois, have invented a certain new and useful Improvement in Safety Devices for Electric Trains, of which the following is a full, clear, concise, and exact description, reference being had to the accompanying drawings, forming a part of this specification.

It is an object of my invention to provide improvements in interlocking safety devices on cars electrically driven to prevent accidents resulting from the brakes being in a condition to prevent control of the train.

My invention is particularly applicable to systems of train operation in which one or more cars of the train are equipped with electric motors for driving such cars and these motors are jointly controlled from a master controller located as desired on the train. In common practice several of the cars of the train may be provided with such master controllers and whether there is a motor on one car only or there are motors on several of the cars, the control exercised from each of the controllers governs all of the motors. In systems of this character air brakes are usually employed to stop the train, and my invention specifically consists in means associated with the controlling valves of such air brake system by which if such valves are not properly set to permit the operation of the brakes the control exercised by the controllers is interrupted and can only be restored by properly setting such valves.

In systems of control of the class above described, it is usual to run controlling leads through the train and to connect these leads to the several controllers, such leads being connected to the electromagnetic mechanism employed to operate the motor, or in case several motors are in operation on the train a plurality of such electromagnetic mechanisms are thus connected. An air-controlling valve is usually associated with each controller, and my invention in its simplest form consists in switching means associated with each of such valves for interrupting the main operating circuit of the associated controller if the valve is in a position to prevent the operation of the brakes and for opening the operating circuit governed by this controller at another point if a second switch is in a position to permit the operation of the brakes from that location on the train. In connec-

tion with the system herein disclosed this is accomplished by operating the tripping circuit of the main circuit breaker when a valve located at a position on the train other than that of the controller used at that time in operating the train is in a position to permit the operation of the brakes. This circuit breaker is so connected with the motors and controllers that such controllers are rendered inoperative when the circuit breaker is in release or open position.

My invention further consists in actuating this circuit breaker tripping mechanism when the air pressure in the braking system is insufficient to operate the brakes.

The several drawings illustrating my invention are as follows:

Figure 1 shows in diagrammatic view my system as applied to a train of two cars, and shows the associated operating mechanism and brake-controlling mechanism used on each end of each car. Figs. 2 and 3 are detailed views of a preferable form of construction of switch to be operated by one of the air valves to be described. Fig. 4 is a detailed view of the air cylinder for operating a safety switch, as will also be described.

Referring to Fig. 1, C, C¹, C² and C³ represent the electric controllers located one on each end of each of the cars of the train, the dividing line between these cars being indicated by the dotted line x—y. Associated with each controller is a brake-operating mechanism designated by V, V¹, V² and V³. Since the several controllers are identical in their construction and operation, it is only necessary to describe one of them, as C, in which the several contacts, as 4, 5, 1, 3, 10, 8, 9 and 11 are adapted to make contact with the contact blocks c, c¹ to c¹⁷, according to the operation of the controller C. These several contacts and contact blocks are connected as follows: Contacts 5 and 1 are connected together and to contact point 19 of switch s¹ by wire 29. Contact points 3, 10, 9 and 11 are connected together. Contact point 8 is connected by wire 28 with one terminal of the magnetic blow-out coil 33. Contact point 4 is connected to contact 14 of switch s² and to train wire 6 by wire 32. Three train wires, 2, 6 and 7, are shown extending from one end of the train to the other and connected from one car to the other by jumper connectors, and these wires are used for the purpose of controlling the motor mechanism on any one or all of the cars from any one of the control-

lers on the train. I have herein shown only sufficient of these train wires to illustrate the operation of my safety system, and it will be understood that in practice for perfectly controlling the motor mechanism more of these train wires are made use of. The magnetic blow-out coil 33 is connected by its other terminal through wire 27, through a fuse as indicated, to the pivotal point of switch s , which 5 serves to cut the controller C into circuit or out of circuit, as desired. The wire 27 also connects to the pivotal point of switch s^2 , which is designed to occupy a central or neutral position when not held in one of its operative positions by the motorman. This 10 switch s^2 is adapted to make contact with the contact points 13 and 14 connected respectively by wires 31 and 32 to the train wires 7 and 6 and operates in a manner and for a purpose 15 to be described later. The contact 12 of switch s is connected by wire 26 and wire 25 with the trolley T by which power is supplied to the controller C to operate the motor-controlling mechanism. A third rail shoe 36 20 is shown connected with the trolley T by wire 24, indicating the adaptability of my system to either third rail systems or overhead trolley systems.

The main circuit through the motor mechanism of the car may be traced as follows: 30 trolley T, wire 25, contact 52, switch 51, wire 53, contact 54 of a circuit breaker 55, to and through an overload solenoid coil 48, wire 47, armature winding M, field winding f, switch 35 46, contact 45, resistance r' , armature winding M of a second motor, field winding f of such motor to ground.

The circuit breaker 55 is adapted to be closed by solenoid 38 acting upon a core 44 40 suitably secured to the switching arm of such solenoid, a spring 56 is provided to maintain the arm 55 normally in position shown in Fig. 1. A latch 58 is associated with the circuit breaker 55 to hold the switch lever in contact 45 with contact point 54 when such circuit breaker is closed, this action of the latch 58 being due to the spring 57, which moves the latch around on the pivot 59 to engage the switch lever, as is apparent from the drawing. 50 Means are provided for releasing the circuit breaker, consisting in either one of two coils, 48 or 49, adapted to act upon the core 50 and thus to move the latch 58 out of engagement with the switch lever 55 and permit the 55 spring 56 to open circuit between the contact 54 and such switch lever. The solenoid winding 38 is connected from train wire 7 through a suitable fuse by wire 37, wire 39 and resistance r^2 to ground. The coil 48 is in 60 series with the motor armatures at all times and constitutes an overload release for tripping the circuit breaker when the current in the motor armature becomes excessive. The coil 49 is connected between the train wire 6 65 and resistance r^2 to ground. The coil 48 is through a suitable fuse as indicated to ground.

The air brake controlling system shown in connection with this invention consists in a motor M' adapted to drive an air pump P connected to an air tank R and supply pipe p for furnishing air as required to operate the 70 braking mechanism. This pipe p extends throughout the train, as does a second pipe p^1 known as the train pipe. Connections are made from the pipes p and p^1 at each position of control by pipes p^2 and p^3 respectively through valves v and v^1 to a controlling valve of a type well known in the art. A third pipe p^4 known as the exhaust pipe is also connected to this operating valve. A valve v^2 is connected with the train pipe p^1 , 80 and there are also connected to this valve an air tank R^1 and operating cylinder 23 for operating the brakes. The valve v^2 is adapted to be operated in such a manner that when the pressure in the pipe p^1 reaches 85 a certain amount this valve is operated to open a passageway between the pipe p^1 and the tank R^1 . This condition is maintained as long as the pressure in the pipe p^1 is maintained, and when the air is permitted to 90 escape from the pipe p^1 and the pressure is thereby diminished below a certain predetermined amount, the valve v^2 operates to form a passage between the tank R^1 and the cylinder 23, as a result of which the air in the 95 tank R^1 serves to set the brakes in a manner well known. When the pressure in the pipe p^1 is again increased to the amount required to operate the valve v^2 , connection is again established between the pipe p^1 and the tank 100 R^1 through such valve and an exhaust passage is opened from the cylinder 23 by which the brakes are released. The switch s^1 mentioned above is associated with the valve v^1 in such a manner that when this valve occupies an open position connection is made between contacts 18 and 19 by such switch. It is to be noticed that the handles of the valves v and v^1 are so proportioned that it is necessary to open the valve v before the 110 valve v^1 can be opened, and it is therefore provided by this device that air may be supplied through the controlling mechanism v for operating the brakes before the motors on the train can be operated, since for this 115 condition the switch s^1 must be closed, as will be explained.

In operating my mechanism the main switch 51 is first closed, controller switch s is closed and the valves v and v^1 are moved to 120 the open position, that is, the position indicated for the brake-controlling mechanism V . The switch s^2 is then moved to make contact with the contact 13, as a result of which the following circuit is closed: trolley 125 T, wire, 25, wire 26, contact 12, switch s , switch s^2 , contact 13, wire 31, train wire 7, wire 37, coil 38, wire 39, resistance r^2 to ground. The momentary energization of this circuit by the operation of switch s^2 130

causes the switch lever 55 to engage the contact 54, for which position the latch 58 is moved by the spring 57 to engage such lever and maintain it in closed position. Then 5 the controller C is moved from the position indicated so that the several contacts make contact with different ones of the contact blocks, as a result of which a circuit is established as follows; if the controller is moved so 10 as to bring contact block c^2 into engagement with contact 1, which is the direction for forward motion of the motors: trolley T, wire 25, wire 26, contact 12, switch s , wire 27, coil 33, wire 28, contact 8, contact block c^6 , 15 contact block c^7 , contact 9, contact 3, contact block c^3 , contact block c^2 , contact 1, wire 29, contact 19, switch s^1 , wire 30, to train wire 2, wire 40, coil 41, resistance r^3 to ground. As a result of this circuit the core 20 43 is actuated and switch 46 is closed, establishing the following circuit through the motors: trolley T, wire 25, contact 52, switch 51, wire 53, contact 54, circuit breaker 55, coil 48, wire 47, armature winding M, 25 field winding f , switch 46, contact 45, resistance r^1 , armature winding M of a second motor, field winding f of such motor to ground. For this position of the controller C it will be understood the contact block c^8 is 30 moved out of contact with the contacts 4 and 5. The successive positions of the controller C result in varying the resistance r^1 and the relation to each other of the motors M, M, in a manner well known in the art but 35 forming no part of this invention.

In the event that the controller C is moved in the opposite direction for the purpose of reversing, similar circuits are closed to those traced above through this controller by 40 which an identical operation of the motor-controlling mechanism is effected. The switch s^2 is adapted to release the circuit breaker 55, if moved to make contact with the contact 14, a circuit being traced for this 45 condition as follows: trolley T, wire 25, wire 26, contact 12, switch s , switch s^2 , contact 14, wire 32, train wire 6, coil 49 to ground, as a result of which the latch 58 is moved out of engagement with the lever of the circuit 50 breaker 55 for which condition the spring 56 opens connection between this lever and the contact 54. From the circuit above traced through the controller it will be apparent that if the switch s^1 were not in a position 55 shown in connection with the brake operating mechanism V it would be impossible to operate the solenoid 41 and therefore to close the motor circuit, and since the handles of the valves v and v^1 interlock, it is necessary 60 that both of these valves be in the open position as shown, in order to close switch s^1 and thereby render the circuit closed by the controller C effective. All of the controllers are shown in the neutral position, and if for 65 the condition of the valves v and v^1 shown in

connection with the brake-operating mechanism V operation of the car were attempted from another controller after properly adjusting the valves connected with such controller, as well as the several switches already 70 described, a circuit would be traced through the switch s^1 and the controller C as follows: train wire 2, wire 30, contact 18, switch s^1 , contact 19, wire 29, contact 5, contact block 8, contact 4, wire 32, to train wire 6. That 75 is, the improper position of the switch s^1 for the operation of the train from another location closes a path of low resistance between the train wires 2 and 6, which results in maintaining the energization of the tripping coil 49 when any of the other controllers is moved to actuate the solenoid 41 to thereby close the motor circuit. From this it appears that it is necessary for the several valves v^1 to all occupy the closed position 80 indicated for the brake-operating mechanisms V^1 , V^2 and V^3 in order to permit the operation under normal conditions of the motor mechanism of the train from the controller C. The inability to operate the train from any 85 one of the controllers is therefore a positive indication to the motor man that some of the air valves on the braking system are incorrectly set and that it is not safe to proceed under this condition. 90

In my system I also provide means for preventing the operation of the train when the air pressure is insufficient for operating the brakes consisting in an air-operated switch connected with the supply pipe p^2 , such 100 switch consisting in cylinder 20 adapted to contain a piston 21 normally held to the right by a spring 22, for which position a switch blade 17 makes contact with the contacts 15 and 16, for which condition a circuit 105 is closed between the train wires 2 and 6 as follows: train wire 2, wire 35, contact 16, switch 17, contact 15, wire 34, to train wire 6, and thus a low resistance path is closed between the train wires 2 and 6 with the same 110 result produced by the other low resistance path just described. When the air pressure is sufficient to operate the brakes, however, the piston 21 is moved in the cylinder 20 to the left and the switch 17 is moved out of engagement with the contacts 15 and 16. 115

In Figs. 2 and 3 a form of construction of the switch s^1 is indicated by which such switch may be readily attached to any of the well known types of valves used for controlling 120 the brake mechanisms. The valve v^1 located in pipe p^3 is provided with an operating handle 60 in which is secured a screw 61 engaging by means of a slot the left hand end of a lever 62 pivoted at 64 to a supporting 125 base 65 of insulating material. The lever 62 has secured to it, but insulated therefrom, the switch blade s^1 adapted to make contact with the contacts 18 and 19 when moved to the position shown in Fig. 2, or to be dis- 130

engaged from them when the handle 60 is moved to the vertical position. The base 65 is adapted to be supported from the pipe p^3 by means of a bracket 66 and clip 67, as indicated.

The air-controlled switch above described may be adapted to be regulated for various pressures by means of a construction indicated in Fig. 4, in which the spring 22 is held 10 in position by a threaded plug 68 screwed into the end of the cylinder 20, by which as the plug is screwed into or out of the cylinder the tension on the spring 22 may be regulated as desired and thus the switch 17 may 15 be caused to operate for various air pressures.

While I have shown my invention in the particular embodiment herein described, I do not, however, limit myself to this construction, but desire to claim broadly any 20 equivalent modifications that will suggest themselves to those skilled in the art.

What I claim as new and desire to secure by Letters Patent is:

25 1. In combination with a car adapted to be electrically driven, two controllers on such car for operating the same, brakes carried by such car, mechanism associated with each of such controllers for controlling such 30 brakes, and means operated by one of such controllers for opening the motor circuit of such car when such controller is moved to an operating position and the brake-controlling mechanism associated with the other controller is in a condition to prevent the application 35 of the brakes from the operating controller.

2. In combination with a car adapted to be electrically driven, two controllers on 40 such car for operating the same, brakes carried by such car, mechanism associated with each of such controllers for controlling such brakes, and means operated by one of such controllers for opening the motor circuit of such car when such controller is moved to an 45 operating position and the brake-controlling mechanism associated with the other controller is in an improper condition for the use of the operating controller.

50 3. In combination with a car adapted to be electrically driven, two controllers on such car for operating the same, air brakes carried by such car, a valve associated with each of such controllers for controlling such 55 brakes, and means operated by one of such controllers for opening the motor circuit of such car when such controller is moved to an operating position and the valve associated with the other controller is in a position to 60 prevent the application of the brakes from the operating controller.

4. In combination with a car adapted to be electrically driven, two controllers on such car for operating the same, air brakes carried 65 by such car, a valve associated with each of

such controllers for controlling such brakes, and means operated by one of such controllers for opening the motor circuit of such car when such controller is moved to an operating position and the valve associated with the other controller is in an improper position for the use of the operating controller. 70

5. In combination with a car adapted to be electrically driven, two controllers on such car for operating the same, air brakes carried 75 by such car, a valve associated with each of such controllers for controlling such brakes, a switch associated with each of such valves, and means operated by one of such controllers for opening the motor circuit of such car 80 when such controller is moved to an operating position and the switch associated with the other controller is in a proper position to operate the car from such other controller. 85

6. In combination with a car adapted to be electrically driven, two controllers on such car for operating the same, air brakes carried by such car, a valve associated with each of such controllers for controlling such brakes, 90 means operated by one of such controllers for opening the motor circuit of such car when such controller is moved to an operating position and the valve associated with the other controller is in a position to prevent the application 95 of the brakes from the operating controller, and means for opening such motor circuit consisting in a circuit adapted to be closed when the air pressure in such brake system is insufficient. 100

7. In combination with a car adapted to be electrically driven, two controllers on such car for operating the same, air brakes carried by such car, a valve associated with each of such controllers for controlling such brakes, 105 means operated by one of such controllers for opening the motor circuit of such car when such controller is moved to an operating position and the valve associated with the other controller is in an improper position for the use of the operating controller, and means for opening such motor circuit consisting in a circuit adapted to be closed when the air pressure 110 in such brake system is insufficient. 110

8. In combination with a car adapted to be electrically driven, two controllers on such car for operating the same, air brakes carried by such car, a valve associated with each of such controllers for controlling such brakes, a switch associated with each of such valves, 115 means operated by one of such controllers for opening the motor circuit of such car when said controller is moved to an operating position and the switch associated with the other controller is in a proper position to operate 120 the car from such other controller, and means for opening such motor circuit consisting in a circuit adapted to be closed when the air pressure in such brake system is insufficient. 125

9. In combination with a car adapted to 130

by such car, a valve associated with each of such controllers for controlling such brakes, means operated by one of such controllers for opening the motor circuit of such car 5 when such controller is moved to an operating position and the valve associated with the other controller is in a position to prevent the application of the brakes from the operating controller, means for opening such motor circuit consisting in a circuit adapted to be closed when the air pressure in such brake system is insufficient, and means for opening such motor circuit when the valve associated with the operating controller is in an inoperative 10 position.

18. In combination with a car adapted to be electrically driven, two controllers on such car for operating the same, air brakes carried by such car, a valve associated with each of 20 such controllers for controlling such brakes, a switch associated with each of such valves, means operated by one of such controllers for opening the motor circuit of such car when said controller is moved to an operating 25 position and the switch associated with the other controller is in a proper position to operate the car from such other controller, means for opening such motor circuit consisting in a circuit adapted to be closed when 30 the air pressure in such brake system is insufficient, and means for opening such motor circuit when the valve associated with the operating controller is in an inoperative position.

19. In a system of train control, a plurality of cars adapted to be electrically driven, electric conductors extending through the train, a controller on one of such cars adapted to control the motor circuit of such 40 train through such conductors, air brakes carried by such cars, a valve on another of such cars for controlling the operation of such brakes, and means associated with such valve for opening such motor circuit when 45 such valve is in an improper position for the operation of the train from such controller.

20. In a system of train control, a plurality of cars adapted to be electrically driven, electric conductors extending through the train, a controller on one of such cars adapted to control the motor circuit of such train through such conductors, air brakes carried by such cars, a valve on another of such cars for controlling the operation of such brakes, a circuit breaker in circuit with 50 such controller for protecting the motor or motors of such train, and means for tripping such circuit breaker when such controller is moved from its neutral position and the 55 valve is in an improper position for the operation of the train from such controller.

21. In a system of train control, a plurality of cars adapted to be electrically driven, electric conductors extending through the train, a controller on one of such cars 60

adapted to control the motor circuit of such train through such conductors, air brakes carried by such cars, a valve on another of such cars for controlling the operation of such brakes, a circuit breaker in circuit with 70 such controller for protecting the motor or motors of such train, a switch associated with such valve adapted to close a circuit through such controller to trip the circuit breaker when such controller is moved from 75 a neutral position and such valve is in an improper position for the operation of the train from such controller.

22. In a system of train control, a plurality of cars adapted to be electrically driven, electric conductors extending through the train, a controller on one of such cars adapted to control the motor circuit of such train through such conductors, air brakes carried by such cars, a valve on another of 80 such cars for controlling the operation of such brakes, a circuit breaker in circuit with such controller for protecting the motor or motors of such train, a switch associated with such valve adapted to close a circuit through 85 such controller to trip the circuit breaker when such controller is moved from a neutral position and such valve is in an improper position for the operation of the train from such controller, and means for closing such tripping circuit when the air in such braking system is insufficient.

23. In a system of train control, a plurality of cars adapted to be electrically driven, electric conductors extending through the train, 100 a controller on each of such cars adapted to control the motor circuit of such train through such conductors, air brakes carried by such cars, a valve associated with each of such controllers for controlling the operation 105 of such brakes, and means associated with each valve for opening such motor circuit when any of such valves is in an improper position for the operation of the train.

24. In a system of train control, a plurality of cars adapted to be electrically driven, electric conductors extending through the train, a controller on each of such cars adapted to control the motor circuit of such train through such conductors, air brakes carried 110 by such cars, a valve associated with each of such controllers for controlling the operation of such brakes, and means associated with each valve for closing a circuit through any one of such controllers when such controller 115 is moved to operate the train and one of such valves on another part of the train is in an improper position, such circuit operating through such conductors to open the motor circuit of the train.

25. In a system of train control, a plurality of cars adapted to be electrically driven, electric conductors extending through the train, a controller on each of such cars adapted to control the motor circuit of such train 120

through such conductors, air brakes carried by such cars, a valve associated with each of such controllers for controlling the operation of such brakes, a circuit breaker in circuit 5 with the motor or motors of the train, a switch associated with each of such valves, and means for closing the tripping circuit of such circuit breaker through one of such switches and thereby opening the motor 10 circuit of the train when the associated valve is in an improper position for the operation of the motor or motors from another part of the train.

26. In a system of train control, a plurality 15 of cars adapted to be electrically driven, electric conductors extending through the train, a controller on each of such cars adapted to control the motor circuit of such train through such conductors, air brakes carried 20 by such cars, a valve associated with each of such controllers for controlling the operation of such brakes, a circuit breaker in circuit with the motor or motors of the train, a switch associated with each of such valves, 25 and means for closing the tripping circuit of such circuit breaker through one of such switches and thereby opening the motor circuit of the train when the associated valve is in an improper position for the operation of 30 the motor or motors from another part of the train and when the controller there located is moved to a position adapted to normally close the motor circuit of the train.

27. In a system of train control, a plurality 35 of cars adapted to be electrically driven, electric conductors extending through the train, a controller on each of such cars adapted to control the motor circuit of such train through such conductors, air brakes carried 40 by such cars, a valve associated with each of such controllers for controlling the operation of such brakes, a circuit breaker in circuit with the motor or motors of the train, a switch associated with each of such valves, 45 any one of such switches serving to close a low resistance path between two of such conductors when the associated valve is in an improper position for the operation of the motor or motors from another part of the 50 train and to thereby operate the tripping circuit of such circuit breaker when a controller not associated with such switch is moved from its neutral position.

28. In a system of train control, a plurality 55 of cars adapted to be electrically driven, electric conductors extending through the train, a controller on each of such cars adapted to control the motor circuit of such train through such conductors, air brakes carried 60 by such cars, a valve associated with each of such controllers for controlling the operation of such brakes, a circuit breaker in circuit with the motor or motors of the train, a switch associated with each of such valves,

any one of such switches serving to close a 65 low resistance path between two of such conductors when the associated valve is in an improper position for the operation of the motor or motors from another part of the train and to thereby operate the tripping 70 circuit of such circuit breaker when a controller not associated with such switch is moved from its neutral position, and means for closing a similar low resistance path when the air pressure in the braking system is insufficient. 75

29. In a system of train control, a plurality 80 of cars adapted to be electrically driven, electric conductors extending through the train, a controller on each of such cars adapted to control the motor circuit of such train through such conductors, air brakes carried 85 by such cars, a valve associated with each of such controllers for controlling the operation of such brakes, a circuit breaker in circuit with the motor or motors of the train, a switch associated with each of such valves, any one of such switches serving to close a low resistance path between two of such conductors when the associated valve is in an 90 improper position for the operation of the motor or motors from another part of the train and to thereby operate the tripping circuit of such circuit breaker when a controller not associated with such switch is 95 moved from its neutral position, switching mechanism associated with each controller and adapted to occupy an inoperative position unless manually held in operative position, and means for operating the train when 100 such low resistance path is closed consisting in manually holding one of such switching mechanisms in operative position and operating the associated controller.

30. In a system of train control, a plurality 105 of cars adapted to be electrically driven, electric conductors extending through the train, a controller on each of such cars adapted to control the motor circuit of such train through such conductors, air brakes carried 110 by such cars, a valve associated with each of such controllers for controlling the operation of such brakes, a circuit breaker in circuit with the motor or motors of the train, a switch associated with each of such valves, 115 any one of such switches serving to close a low resistance path between two of such conductors when the associated valve is in an improper position for the operation of the motor or motors from another part of the 120 train and to thereby operate the tripping circuit of such circuit breaker when a controller not associated with such switch is moved from its neutral position, switching mechanism associated with each controller 125 and adapted to occupy an inoperative position unless manually held in operative position, means for operating the train when

such low resistance path is closed consisting in manually holding one of such switching mechanisms in operative position and operating in the associated controller, and means for closing a similar low resistance path when the air pressure in the braking system is insufficient.

In witness whereof, I hereunto subscribe my name this twenty-fourth day of December, A. D. 1907.

ADOLPH H. DAUS.
